(57) **CLAIM**

The ornamental design for an exercise device with flanged bushings for sleeveless tubes as shown and described.

DESCRIPTION

FIG. 1 is a perspective view of an exercise device with flanged bushings for sleeveless tubes showing my new design;

FIG. 2 is a left side view thereof;

FIG. 3 is a right side view thereof;

FIG. 4 is a rear view thereof;

FIG. 5 is a front view thereof;

FIG. 6 is a top view thereof; and,

FIG. 7 is a bottom view thereof.

The broken lines on the middle of the exercise device with flanged bushings for sleeveless tubes depict symbolic break lines. Any appearance of the device between the break lines form no part of the claimed design.
